(57) **CLAIM**

(21) Appl. No.: **29/182,739**

The ornamental design for a combination telephone and clock radio, as shown and described.

(22) Filed: **May 30, 2003**

DESCRIPTION

(51) LOC (7) Cl. **14-03**

FIG. 1 is a front perspective view of the design for the combination telephone and clock radio having attached thereto an environmental feature, namely an antenna; and, FIG. 2 is a rear perspective view of the design for the combination telephone and clock radio of FIG. 1.

(52) U.S. Cl. **D14/144; D14/149**

The broken lines provided in the above views are used to indicate environmental structure and form no part of the claimed design.
